UNITED STATES PATENT OFFICE.

EDWARD JOHN RIDGWAY, OF STATEN ISLAND, NEW YORK.

DESIGN FOR A PLATE OR SIMILAR ARTICLE.

Application filed March 15, 1922. Serial No. 1,182. Term of patent 14 years.

To all whom it may concern:

Be it known that I, EDWARD JOHN RIDGWAY, a subject of the King of Great Britain and Ireland, residing at Staten Island, in the county of Richmond, State of New York, have invented a new, original, and ornamental Design for a Plate or Similar Article, of which the following is a specification, reference being had to the accompanying drawing, forming part thereof.

The figure is a face view of a segment of a plate, showing my new design applied thereto, it being understood that the design

is repeated around the entire circumference of the article. It is to be understood, also, that my design is not limited to application to a plate, but may be applied equally well to articles of crockery and chinaware in general.

I claim:

The ornamental design for a plate or similar article, as shown and described.

In testimony whereof I have signed my name to this specification.

EDWARD JOHN RIDGWAY.
